(57) **CLAIM**

The ornamental design for chain-set jewelry, as shown and described.

DESCRIPTION

FIG. 1 is a perspective view of chain-set jewelry showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a left side elevational view thereof;

FIG. 7 is a right side elevational view thereof;

FIG. 8 is a perspective view thereof shown in an alternate environment;

FIG. 9 is a perspective view thereof shown in an alternate environment;

FIG. 10 is a perspective view thereof shown in an alternate environment;

FIG. 11 is a perspective view thereof shown in an alternate environment;

FIG. 12 is a front elevational view of a second embodiment of chain-set jewelry showing my new design; and,

FIG. 13 is a front elevational view of a third embodiment of chain-set jewelry showing my new design.

The broken lines appearing in the figures are for the purpose of illustrating the environmental structure of the article of the claimed design and form no part of the claimed design.
